Inventor

UNITED STATES PATENT OFFICE.

EDWARD M. RUNDGREN, OF CHICAGO, ILLINOIS, ASSIGNOR TO WESTERN ARCHITECTURAL IRON COMPANY, OF CHICAGO, ILLINOIS.

WINDOW STRUCTURE.

Application filed February 16, 1925. Serial No. 9,384.

To all whom it may concern:

Be it known that I, EDWARD M. RUNDGREN, a citizen of the United States, and a resident of the city of Chicago, county of Cook, and State of Illinois, have invented certain new and useful Improvements in Window Structures, of which the following is a specification.

My invention relates to window structures, and the same has for a main object the provision of an improved window construction which will embody certain desired features of simplicity, efficiency and convenience, which will be economical in manufacture and durable in use.

Another object of my invention is to provide an improved window especially adapted for use in the basements of buildings, in garages, shops and other places; one in which the sash can be readily and quickly removed from the frame and in which means comprising novel weather-proof elements effectually safeguard against the wind and the rain.

Other objects will appear hereinafter.

The invention consists in the combinations and arrangements of parts hereinafter described and claimed.

The invention will be best understood by reference to the accompanying drawings forming a part of this specification, and in which,

Fig. 1 represents an exterior view of a window construction made in accordance with the present invention, this view showing the construction as installed in a wall;

Fig. 2 represents an interior view of the window construction as installed in a wall;

Fig. 3 is a horizontal section taken approximately on line 3—3 of Fig. 2;

Fig. 4 is a vertical section taken approximately on line 4—4 of Fig. 2; and

Fig. 5 represents a vertical sectional view through the window sash.

The preferred embodiment of my invention, as illustrated in the accompanying drawings, includes an all-metal window frame denoted as a whole by the reference character 6 and comprising opposed main side plates 7 to which is welded or otherwise connected a head plate 8. To the main side plates 7 and the head plate 8 are secured, preferably by welding, the angle side plates

9 and the angle head plate 10, respectively. From an inspection of Figs. 3 and 4, it will be seen that the angle side plates 9 are secured intermediate the width of the main side plates 7, so that the outer marginal edges 7' of the main plates may be built or fitted into the wall as 11 to which the window construction is applied, and also that the inner marginal edges 7'' of the main plates may be utilized as abutments for the window sash as will more fully appear hereinafter. Similarly, the head angle plate 10 is secured intermediate the width of the head plate 8, so that the outer marginal edge 8' may be built or fitted into a wall as 11 while the inner marginal edge 8'' is adapted to serve as an abutment for the window sash. The all-metal window frame is completed by welding or otherwise securing to the bottom end thereof the angle sill 12, designed to be secured to or fitted upon a projecting portion 13 of the window ledge or wall 14.

The window sash, designed to be employed in connection with the window frame and herein designated as a whole by the reference character 15, is an all-metal construction produced in a novel manner from T-plates and angle plates. Preferably and as shown, the sash 15 has for its opposed sides the T-shaped side plates 16 to which are welded the angle plates 17, whose angles face outwardly of the structure as shown in Fig. 3. These side T-plates and angle plates 16 and 17 are so fashioned and connected that, upon the application of the sash to the window frame, the cross pieces of the T-plates will contact with the inner marginal edges 7'' of the main frame plates 7, while the outwardly projecting portions of the angle plates 17 will engage over the inner extremities of the angle plates 9 comprising the sides of the frame. The top of the window sash consists of an angle plate 18 which is welded in proper position upon the top ends of the T-plates 16 and angle plates 17. The bottom portion of the window sash comprises a T-plate 19 to which is secured an angle plate 20, these parts being so arranged that, upon the application of the sash to the frame, the cross piece of the T-shaped plate 19 will engage over a half-round weather strip 21 when the angle

plate 20 engages over the inner marginal edge of the frame sill 12, as best illustrated in Fig. 4. Said weather strip 21 is preferably secured upon the frame sill 12 by welding it thereon.

According to an important feature of my invention, the sash 15 is removably set in the window frame, provision being made whereby the sash may be locked to and with the window frame, and provision further being made whereby, when unlocked, the sash may be swung relatively to the frame. From an inspection of Figs. 2 and 4 it will be seen that open bearings 22 are formed in the top ends of the side plates 9 of the window frame; and that there is secured upon the head angle plate 18 of the sash a shaft 23 which is adapted to be removably entered in said open bearings 22 and which is further adapted to have turning fit in said bearings. Another feature of the construction in this connection is that the co-acting members at the head ends of the frame and sash are so arranged that the said shaft 23, when mounted in the bearings 22, will constitute a weather-proof strip between the head angle plate 10 of the frame and the head angle plate 18 of the sash. In applying the sash to the frame, it is only necessary to set the shaft 23 in the bearings 22 and then press the sash into its seat, pushing the sash T-plate 19 over the bottom weather strip 21, it being evident that the shaft 23 will rise in the open bearings 22 in order to permit said T-plate to rise over the said weather strip 21. To swing the sash in the frame, it is only necessary to draw the lower portion outwardly of the frame, sliding the T-shaped plate 19 over the weather strip 21. The sash, in order to be removed from the frame, is lifted upwardly so as to withdraw the shaft 23 from its bearings.

Means are provided for drawing the sash tightly to its seat in the frame and at the same time effecting tight weather-proof contact for the weather strip 21 and the shaft 23 which, as hereinbefore observed, also constitutes a weather strip. In the present embodiment, this means comprises a cam action latch 24 pivoted at 25 to the sash and adapted to co-act with a keeper 26 which is secured to the angle sill 12 of the frame. To this end, in the embodiment shown, the keeper 26 is made with an opening 27 having a tapering wall 28 with which the cam portion 29 of the latch engages in closing so as to press the sash tightly to the frame, the said cam portion 29 also being made with a hooked extremity 30 designed to engage under the keeper so as to draw the sash downwardly, bringing the shaft 23 into tight engagement between the frame angle plate 10 and the sash angle plate 18 and also bringing the cross piece of the T-plate 19 into tight engagement with the weather-proof strip 21.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A window structure including a frame provided with axis receiving members, a sash arranged in the frame, and an axis with turning fit in said receiving members extending along one side of the sash and forming a weatherproof strip between the frame and sash, substantially as described.

2. A window structure including a frame having a head plate, axis receiving members on the frame in relation to the head plate, a sash, and an axis with turning fit in said receiving members extending along the top of the sash and forming a weather-proof strip between the head plate and sash, substantially as described.

3. A window structure including a frame having a head part and a sill, axis receiving members on the frame in relation to the head part, a sash, an axis with turning fit in said receiving members extending along the top of the sash and forming a weather-proof strip between the head and sash, and a flange on the sash contacting with the inner edge of the sill, substantially as described.

4. In a window structure, the combination with a frame having a weather-proof element and axis receiving members, of a sash set in said frame and an axis extending along the top of the sash in weathering contact with the weather-proof element and fitting said receiving members, substantially as described.

5. In a window structure, the combination with a frame having axis receiving members of a sash set in the frame, an axis removably and turnably fitting said receiving members, said axis extending along the top of the sash and constituting a weathering contact between the frame and sash, substantially as described.

6. In a window structure, the combination with a frame having axis receiving members, of a sash set in the frame, an axis removably and turnably fitting said receiving members and contacting along the top of the frame to constitute a weather-proof strip, and cooperative means on the sash and frame for drawing said sash and axis into tight contact with said frame, substantially as described.

7. In combination, a window frame, a

weather strip attached to the frame, open bearing members carried by the frame in opposed relation to said weather strip, a sash fitting in the frame, an axial member along one edge of the sash adapted to and bearing in said open bearing members and having weathering contact with the frame, and flange members on said sash adapted to engage over the outer side of said 10 weather strip and the inner side of said frame substantially as described.

8. In combination, a window frame including a sill, a weather strip thereon, open bearing members carried by the frame in opposed relation to said weather strip, a sash set in the frame, an axial member on the sash having weathering contact with the frame and bearing in said bearing members, and a pair of flange members fixed on 15 the sash adapted respectively to cooperate with the inner edge of the sill and the outer 20

face of the weather strip thereon, substantially as described.

9. In a window structure, the combination with a frame having axis receiving members thereon, a window strip attached to the frame in relation to said receiving members, a sash set in said frame, an axial member along the sash affording a weathering contact with the frame and fitting said 25 receiving members, a flange on the sash adapted to cooperate with said weather strip, and a cam action latch for drawing the sash in a direction to tighten the weathering contact between the axial member and frame, and between said flange and said weather strip, substantially as described. 30 35

In testimony whereof I have signed my name to this specification.

EDWARD M. RUNDGREN.
